Primary Examiner—M. N. Pandozzi*(74) Attorney, Agent, or Firm*—Rosenberg, Klein & Lee(57) **CLAIM**

I claim, the ornamental design for a surface pattern applied to a cup, as shown and described.

DESCRIPTION

FIG. 1 is a perspective view of a surface pattern applied to a cup showing my present design;

FIG. 2 is a front view thereof;

FIG. 3 is a rear view thereof;

FIG. 4 is a left view thereof;

FIG. 5 is a right view thereof;

FIG. 6 is a top plan view thereof; and,

FIG. 7 is a bottom plan view.

The broken lines shown in FIGS. 1, 6, 7 are for illustrative purposes only and form no part of the claimed design.
